Primary Examiner — Cynthia Ramirez*Assistant Examiner* — Michael Maharajh(74) *Attorney, Agent, or Firm* — Knobbe Martens Olson & Bear, LLP**CLAIM**

The ornamental design for a tight head drum, as shown and described.

DESCRIPTION

FIG. 1 is a top perspective view of a tight head drum showing my new design;

FIG. 2 is a front elevational view; the rear elevational view being a mirror image of FIG. 2;

FIG. 3 is a right elevational view; the left elevational view being a mirror image of FIG. 3;

FIG. 4 is a top plan view thereof; and,

FIG. 5 is a bottom plan view thereof.

The broken lines in the drawings are included for the purpose of illustrating environment and form no part of the claimed design.
